DESIGN FOR A FIREPLACE-FRONT.

SPECIFICATION forming part of Design No. 38,072, dated September 9, 1902.

Application filed July 29, 1902. Serial No. 117,591. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Fireplace-Fronts, of which the following is a full, clear, and exact description, reference being had to the accompanying drawing, forming part hereof, in which the invention is illustrated in front elevation.

The leading features of my design consist of a frame each of the sides of which is ornamented with the representation of an extended vase or candelabrum, from which springs the figure of a woman bearing a beacon-light. The top piece is in the shape of a hood having an ornamental scalloped effect

along its upper and lower edges and a central row of diamond-like figures. The center or summer front has an ornamental border and an oval paneled central portion depicting Cupid seated on a garland of flowers swung from the upper corners of the frame. Below the summer front and extending the width thereof is an open-work frame.

I claim—

The ornamental design for a fireplace-front as herein described and shown.

In testimony whereof I have hereunto set my hand in the presence of two subscribing witnesses.

THOMAS M. DUDGEON.
